STOPPING MECHANISM FOR NARROW WARE LOOMS

Application filed July 9, 1930. Serial No. 466,660.

This invention relates to narrow ware looms and particularly to mechanism for stopping a narrow ware loom. In my prior application, Serial No. 453,369, filed May 17, 5 1930, I have shown a device for disconnecting or disabling the shuttle driving mechanism in a narrow ware loom when normal movement of the shuttles is prevented. With the prior construction, however, all 10 other parts of the loom mechanism continued in operation until the loom was stopped by the weaver.

It is the object of my present invention to provide means by which the entire loom will 15 be stopped when the shuttle drive is disabled, so that no unnecessary or useless operation of the loom may occur.

My invention further relates to arrangements and combinations of parts which will 20 be hereinafter described and more particularly pointed out in the appended claims.

A preferred form of the invention is shown in the drawings, in which

Fig. 1 is a front elevation, partly in section, of portions of a loom embodying my 25 improvements;

Fig. 2 is a sectional end elevation of certain parts, looking in the direction of the arrow 2 in Fig. 1;

Fig. 3 is a front elevation of certain parts shown in Fig. 1 but in a different position, and

Fig. 4 is an end view of certain parts shown in Fig. 2, also in a different position.

Referring to the drawings, I have shown parts of a narrow ware loom of commercial construction and comprising a loom frame 10 in which a lay 11 is mounted to swing forward and rearward. The lay is supported upon the usual swords 12 having hub portions 13 at their lower ends secured to sleeves 15 pivotally mounted in bearing brackets 16 secured to the loom frame 10.

A rack bar 17 is mounted for reciprocating movement on the lay 11 and actuates pinions (not shown) by which the narrow ware shuttles are moved back and forth across the different strips of fabric. The ends of the rack bar 17 are connected to chains 18 passing around upper guide pulleys 19 and se-

cured to lower sprockets 20. A second and smaller sprocket 21 is secured to each lower sprocket 20, the sprockets 20 and 21 rotating in unison about pivot studs 22 in brackets 23 formed on the ends of the sleeves 15 which support the lay swords 12. Additional chains 25 connect the smaller sprockets 21 to the ends of a pull rod 26, the chains 25 and pull rod 26 being slidable substantially in alignment with the axis of the sleeves 15.

A diamond-shaped member or frame 30 (Fig. 3) is slidable on fixed guide rods 31 and is provided with vertical flanges 32 on its rear face, forming a guideway to receive 65 a crankpin 33 on a continuously rotating crank arm 34. The crank arm 34 is mounted on a crank shaft 35 which may be connected by bevel gears 36 to the usual bottom shaft 37 of the loom. As the shaft 35 is rotated, 70 the crankpin 33 moves up and down in the vertical guideway between the flanges 32 and reciprocates the frame 30 on the guide-rod 31.

A U-shaped block 40 (Fig. 3) is mounted 75 on the pull rod 26 and may be adjusted in position thereon by check nuts 41. The sliding frame 30 has a forward projection or abutment 42 positioned below the block 40 and having a semi-circular recess 43 in its 80 upper face.

A disabling connecting member is interposed between the block 40 and the abutment 42. This connecting member comprises two separate elements 45 and 46, 85 hinged together at their adjacent ends by a cross-pin 47. These adjacent ends are shaped to provide a rounded surface closely fitting the recess 43 and adapted to turn therein.

A cross slide 60 is mounted in guideways 62 in the sliding frame 30. A coil spring 64 is mounted on a rod or plunger 65, the lower end of which is secured in a lug 66 formed at the upper end of the cross slide 60. The upper end of the rod 65 slides freely in a guide opening in the upper part of the sliding frame 30. The spring 64 engages nuts 67 on the stud 65 and acts to push the beveled foot portion 70 of the 100

slide 60 against the top surface of the block 40. Such downward movement is resisted by the connecting elements 45 and 46, which elements are thus firmly seated at their lower ends in the recess 43 and at their upper ends in the U-shaped block 40, the position of the parts during normal operation being as shown in Fig. 1.

If movement of the shuttles and corresponding movement of the pull rod 26 is prevented, the block 40 will remain stationary while the sliding frame 30 continues to move, carrying with it the abutment 42. This causes one or the other of the connecting members 45 and 46 to swing to the upright position indicated in Fig. 3 and continued movement of the frame 30 and abutment 42 will cause the connecting members 45 and 46 to be entirely dislocated, these parts then falling to the floor or other supporting surface.

After this occurs, the sliding frame 30 is entirely disconnected from the pull rod 26 and no further movement of the shuttles will take place until the obstruction is removed and the connecting members are reassembled.

The mechanism thus far described is substantially as shown in my prior application, to which reference is made for a more detailed description of the construction and operation of the several parts.

The loom shown in the drawings is provided with the usual loom stopping mechanism including cross shaft 70 (Fig. 2) mounted in bearings 71 on the end of the loom frame 10. The hand rail or shipper rod 72 is provided at the front of the loom and is pivotally connected to an arm 73 at the forward end of the cross shaft 70. An arm 74 at the rear end of the shaft 70 is connected by a link 75 (Fig. 1) to a stud 76 at the front end of a shipper lever 77.

The lever 77 is pivoted on a fixed bracket 78 and is forked as indicated at 79 to engage a clutch sleeve or other driving connection at the rear end of the shipper lever. Movement of the cross shaft 70 is thus effective to start or stop the loom through the action of the shipper lever 77.

An arm 80 (Figs. 2 and 3) is loosely mounted on the cross shaft 70 and is forked at its lower end to embrace a rock shaft 82, mounted in fixed bearings supported by the loom frame and held from endwise movement therein.

An arm 83 is fixed to the cross shaft 70 and has an offset finger 84 positioned for engagement by the arm 80. The lower end of the arm 80 is engaged by a collar 85 slideable on the rock shaft 82 and forced to the left (as viewed in Fig. 1) by a heavy coil spring 86, also mounted on the rock shaft 82 and abutting a collar 87 thereon.

When the arm 80 is free to be moved by

the spring 86, it engages an offset finger 84 of the arm 83 and swings the rock shaft 70 to release the clutch through which the loom is driven. Such movement of the arm 80 is normally prevented, however, by engagement of a lug 88 on the side of the arm 80 with the end of an offset finger 89 on the arm 90 fixed to the rock shaft 82. The rock shaft 82 also has a pair of arms 93 fixed thereto and supporting a contact bar 94, which extends lengthwise of and parallel to the rock shaft 82 and which overlies the upper end of the sliding rod or plunger 65 previously described.

The operation of my improved stopping mechanism is as follows:—

When movement of the shuttles is interrupted as previously described and one of the connecting member 45 or 46 is moved to the position shown in Fig. 3, this action causes an upward sliding movement of the cross slide 60 and a corresponding upward movement of the plunger 65. The plunger underlies the contact bar 94 in every position of the plunger and the upward movement of the plunger forces the bar upward and causes a corresponding rocking movement of the rock shaft 82. Such movement rocks the finger 89 of the arm 90 out of engagement with the lug on the side of the forked arm 80 and permits the arm 80 to move freely from the position shown in Fig. 1 to that shown in Fig. 3. Such movement is communicated through the arm 83 to the cross shaft 70, releasing the clutch and stopping the loom.

I have thus provided operative connections between the shuttle releasing devices and the loom stopping mechanism, such that the loom will stop whenever normal movement of the shuttles is prevented. It will be further evident that the connection from the hand rail 72 to the loom stopping mechanism is such that the loom may be stopped by hand at any time without interfering with the automatic connections.

Having thus described my invention and the advantages thereof, I do not wish to be limited to the details herein disclosed, otherwise than as set forth in the claims, but what I claim is:—

1. In a narrow ware loom, shuttle reciprocating devices, actuating mechanism therefor, a yieldable driving connection between said mechanism and said devices, said connection being disabled if normal movement of said shuttle reciprocating devices is prevented, and means for stopping the loom, said latter means being rendered operative by disablement of said driving connection.

2. In a narrow ware loom, shuttle reciprocating devices, actuating mechanism therefor, a disabling connecting member between said mechanism and said devices, said connecting member being displaced if normal

movement of said shuttle reciprocating devices is prevented, and means for stopping the loom, said latter means being rendered operative by said connecting member as it is displaced.

5. 3. In a narrow ware loom, shuttle reciprocating devices, actuating mechanism therefor, loom stopping mechanism, a connecting member normally inoperative with respect to said stopping mechanism, and connections through which displacement of said connecting member renders said stopping mechanism operative to stop the loom.

10. 4. In a narrow ware loom, shuttle reciprocating devices, actuating mechanism therefor, loom stopping mechanism, a connecting member normally inoperative with respect to said stopping mechanism, a spring-pressed plunger normally holding said member in 15 connecting position, and a device engaged by said plunger and effective to release said stopping mechanism when moved by said plunger upon displacement of said connecting member.

20. 5. The combination in a narrow ware loom as set forth in claim 4, in which the spring-pressed plunger is reciprocated with the shuttle reciprocating mechanism and in which said plunger is effectively operative 25 as to the stopping mechanism in every position of said plunger.

30. 6. In a narrow ware loom, shuttle actuating mechanism, loom stopping mechanism, a give-way connection in said shuttle actuating mechanism, and means to release the loom stopping mechanism, said releasing means being rendered operative by abnormal movement of said give-way connection upon prevention of normal operation of the 35 shuttles.

40. 7. In a narrow ware loom, shuttle actuating mechanism, loom stopping mechanism, a give-way connection in said shuttle actuating mechanism, and a knock-off device for 45 said loom stopping mechanism, rendered operative by abnormal movement of said give-way connection upon prevention of normal operation of the shuttles.

50. In testimony whereof I have hereunto affixed my signature.

ELBRIDGE R. HOLMES.
